CLAIM

The ornamental design for a heart shaped container, as shown and described.

DESCRIPTION

FIG. 1 is a front, right and top perspective view of a heart shaped container with the two parts in a disassembled status, showing my new design;

FIG. 2 is a front, right and top perspective view of the heart shaped container shown in an alternate configuration with the two parts in an assembled status;

FIG. 3 is a rear, left and bottom perspective view of the heart shaped container shown in an alternate configuration with two parts in a disassembled status;

FIG. 4 is a rear, left and bottom perspective view of the heart shaped container shown in an alternate configuration with the two parts in an assembled status;

FIG. 5 is a front view of the first part of the heart shaped container, shown separately to show aspects of the design that are not visible when combined;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a front view of the second part of the heart shaped container, shown separately to show aspects of the design that are not visible when combined;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.
